UNITED STATES PATENT OFFICE.

LIONEL DE GOURNAY, OF NANTES, FRANCE.

OVEN FOR THE MANUFACTURE OF OVOID OR OTHER SHAPE SMOKELESS BRIQUETS.

No. 826,027.

Specification of Letters Patent.

Patented July 17, 1896.

Application filed June 6, 1904. Serial No. 211,347.

To all whom it may concern:

Be it known that I, LIONEL DE GOURNAY, president of la Compagnie des Charbons et Briquettes de Blanzy et de l'Ouest, of 3 Place de la Petite Hollande, Nantes, Loire-Inférieure, in the Republic of France, have invented Improvements in Ovens for the Manufacture of Ovoid or other Shape Smokeless Briquets; and I do hereby declare the nature of this invention and in what manner the same is to be performed to be particularly described and ascertained in and by the following statement.

This invention relates to an improved form 15 of carbonizing or coking oven for coking or carbonizing briquets made of coal or coke dust combined with suitable combining agents—such as resin, coal-tar, or the like—and suitable supporters of combustion—20 such, for instance, as nitrate or carbonate of potash or sodium.

The invention has to do particularly with the form of oven employed in such processes whereby the volatile matter of the coal and 25 various chemical agents associated therewith in the composition of the briquet may be effectively distilled.

The invention consists in the provision of an improved oven for the purpose set forth 30 consisting of a plurality of briquet or coking chambers, together with the provision of suitable means for applying heat thereto, the chambers being arranged and connected in such a manner that an internal pressure of 35 the distilled volatile gases is created sufficient to overcome the normal external air-pressure and effectively cause a continuous and complete discharge of the gases during the coking or carbonizing process.

40 The invention will be described in connection with the accompanying drawings and will be more particularly ascertained and pointed out in the appended claims.

In the drawings, Figure 1 is a longitudinal 45 vertical section of an oven comprising a series of superposed chambers constructed in accordance with my invention. Fig. 2 is a vertical section on line C D of Fig. 1. Fig. 3 is a vertical section of the preferred construction consisting of a single series of connected chambers. Fig. 4 is a horizontal sectional view of a portion of one chamber, showing controller for the discharge-outlet.

The invention consists generally of a struc-

ture provided with a horizontally-disposed series of connected chambers extending lengthwise throughout the oven and divided by transversely-disposed partition-walls, each chamber preferably extending laterally throughout the width of the oven and provided with openings through the lateral walls thereof to provide means for charging or placing the briquets and discharging the same from said chambers, the said openings during the coking or carbonizing process being closed by suitable means. Each of the transverse walls of the compartments are provided with apertures connecting said compartments with each other, the outermost or end compartments having openings 70 for discharging the gases into suitable collectors, the gases from the innermost compartments passing through said openings and through each compartment to the outermost or end compartments. In order to effect 75 such discharge of the gases, the openings in the transverse walls are so arranged with respect to each other and are made of such size as to create a pressure in the innermost or central compartments and cause a gradual 80 accumulation and a consequent pressure of the gases in their outward travel to the outermost compartment, causing effective discharge therefrom. This feature is realized by providing the transverse walls of the innermost or central chambers with openings 85 of a size sufficient to permit free discharge of the normal volumes of gases therefrom.

The apertures in the adjacent or outwardly-located chambers are each enlarged with respect to the apertures of the central or innermost chambers; but the enlargement is not sufficient to permit free discharge of the gases, but is somewhat restricted with respect to the volume of gas to be discharged 90 from each chamber to effect the accumulation and consequent pressure above set forth. In order to more fully realize this feature of the invention, auxiliary means for creating such pressure may be provided by locating 100 the apertures in the transverse walls in staggered relation or out of alignment, so that the gases in passing through the aperture of one compartment will be directed against the imperforate portion of the next partition-wall, whereupon they will be compelled to travel laterally to the next aperture.

The invention is shown in Figs. 1 and 2

embodied in a furnace containing three series of superposed compartments, although the preferred form is shown in Fig. 3, wherein a single series of compartments is illustrated.

5 For convenience the invention will be described first in connection with Figs. 1 and 2, wherein is shown an oven provided with a central longitudinally-disposed heating-chamber B' , closed at both ends and, as shown, provided with a pipe B^2 for supplying gas or other heating agency. It will be understood that any other suitable means may be provided for heating the oven. The products of combustion pass upwardly 15 through vertical flues b' , which discharge into transverse flues b^2 , the latter extending substantially throughout the width of the furnace. Each transverse flue b^2 delivers to longitudinally-disposed flues b^3 , wherefrom 20 the products of combustion pass to suitable discharge-pipes b^4 .

It will be understood that means for carrying the products of combustion from the combustion or generating chamber B' may 25 be varied in any desired manner to effect an economical and efficient utilization by the oven of the heat units. There is located immediately above the flues just described a series of longitudinally-disposed chambers A , 30 which are divided from said flues by a relatively thin wall b^5 in order that the said chambers may be effectively heated. Said chambers A are formed by the wall b^5 and upper wall b^6 and transverse partitions A' . 35 There is superposed upon the compartments just described two additional series A^2 and A^3 , provided with a top wall A^4 , and each of these series is also separated by transverse walls A' .

40 In order to effect sufficient heating of the material in the upper chambers, the intervening walls A^5 between each series of compartments will be made of material having a high degree of heat conductivity, and the 45 briquet may be sorted, so that briquets requiring an application of heat at a high temperature may be placed in the lower series of compartments, while those requiring heat of a lower temperature will be placed in the upper series of compartments. Each of the 50 compartments of each series from A to A^3 extend throughout the width of the furnace and are provided with suitable removable closures A^5 , A^6 , and A^7 . In inserting the 55 briquets in the compartments the closures will be removed, and when the coking process is started they will be replaced, so that the distilled gases will be discharged in the prescribed manner.

60 Each of the transverse partitions A' is provided with a plurality of apertures a , connecting adjoining compartments, and the outer or end compartments are also provided with apertures delivering to any suitable

form of gas-collector a^2 . The apertures near 65 the central compartments are of sufficient size to permit the escape of the normal volumes of gas to be discharged from said compartment. The apertures of the next outwardly-adjoining compartments are slightly 70 increased in size with respect to said first-mentioned apertures, and in the succeeding outer partitions the apertures are slightly and gradually increased in size. The gas from the central compartments traveling to 75 the next adjoining outer compartments will effect therein a gradual accumulation and a consequent pressure exceeding the discharging capacities of said apertures, and this accumulation will cause a pressure in each compartment, which, finding no access in a central direction, will travel outwardly to the collector a^2 , the said openings a of each compartment being slightly reduced with respect to the volume of gas to be discharged. By 80 means of this construction the danger of explosions in the innermost or central compartments is eliminated. It will be understood, however, that the closures A^5 to A^7 will not be firmly secured in place, so that if the apertures should clog and prevent proper escape of accumulating gases the same could force egress through the lateral openings of the oven. It will be understood that in an arrangement of this nature it will be easy to 85 determine the relative sizes of the apertures a with respect to the size of the chamber, so that the volume of discharging gases could be restricted to create the desired internal pressure. If, however, any difficulty in this 90 respect were encountered, any suitable form of regulator device, such as shown in Fig. 4, may be employed and regulated from the exterior of the oven. As shown, this form of 95 regulator consists in providing slides D within each compartment and having openings equal to the apertures a , so that by moving the slides slightly out of register with 100 said apertures the discharging capacity of the same may be varied.

105 In order to create a more effective internal pressure, the apertures a of the transverse partitions may be disposed in staggered relation, as shown in Figs. 1 and 2, so that the gases passing from one chamber to the other 110 will first engage its outermost wall and from thence be directed laterally to the nearest aperture therein, the resistance from this change in the course of the gases creating an additional pressure.

115 I claim—

1. An oven for carbonizing briquets provided with a plurality of compartments communicating with each other by longitudinally-disposed openings arranged in staggered relation and increasing in size from the innermost to the outermost compartment.

120 2. An oven for carbonizing briquets pro-

vided with a plurality of compartments communicating with each other by longitudinally-disposed openings increasing in size from the innermost to the outermost compartment, whereby the resultant pressure forces the gases outwardly from the innermost to the outermost compartments.

In testimony that I claim the foregoing I have hereunto set my hand this 19th day of May, 1904.

LIONEL DE GOURNAY.
